UNITED STATES PATENT OFFICE.

CHARLES A. UPSON, OF LOCKPORT, NEW YORK.

FASTENING DEVICE FOR WALL-BOARD, &c.

1,324,483.

Specification of Letters Patent.

Patented Dec. 9, 1919.

Application filed May 28, 1919. Serial No. 300,384.

To all whom it may concern:

Be it known that I, CHARLES A. UPSON, a citizen of the United States, residing in Lockport, in the State of New York, have 5 invented certain new and useful Improvements in Fastening Devices for Wall-Board, &c., of which the following is a specification, reference being had to the accompanying drawings, forming a part hereof.

10 This invention relates to fastening devices for wallboard, etc., of the same general character as that shown and described in Letters Patent of the United States granted to Julius E. B. With, No. 1,297,523, dated 15 Mar. 18, 1919, and in Letters Patent of the United States granted to the present applicant, No. 1,297,611, dated Mar. 18, 1919, and it has for its object to cover a specific form 20 of such fastening device which may be of advantage under some conditions of use or with some kinds of material. In the forms 25 of fastening devices shown in said several Letters Patent the prongs which are struck up from the plate are shown as inclined outwardly or away from each other, although they are described and covered only as spreading laterally without regard to their inclination toward or from each other. In 30 the specific form of the fastener which is the subject of the present invention such struck-up prongs, or some of them, are inclined or bent toward each other so that, when they enter the material, they may have something of a clenching action. Another feature of 35 the improvement has for its special object facility in manufacture and in use. The invention will be more fully explained hereinafter with reference to the accompanying drawing in which it is illustrated, and in 40 which—

Figure 1 is a view of the improved fastener in elevation, before the edge and face prongs are bent.

Fig. 2 is a view of the same as seen from 45 the left hand in Fig. 1, but with the edge prong bent into position for application to the studding and the face prongs bent to engage the wallboard.

Fig. 3 is a view of the same as seen from 50 above in Fig. 2, the position of the wallboard, as it is being applied, being also shown.

Fig. 4 is a side view similar to Fig. 3, but showing the wallboard driven home from the fastener.

The improved fastener consists of a thin, flat, metal plate *a* of any desired form, it being shown in the drawing as generally rectangular. It has, extending from one edge outward, a wide prong *b*, which may 55 be stiffened by corrugation as at *b'*, which may be driven into the studding to which the wallboard is to be secured. In its other side, extending outward from the edge, is a corresponding notch *b*², which may be 60 utilized as a nailing slot, if so desired. The formation of the plate in this manner, with a prong on one side and a corresponding notch in the other side, permits the fastener to be stamped out from a strip or sheet of 65 metal without waste. The plate has also, preferably struck up because of economy in manufacture, two prongs *c* which are 70 slightly bent toward each other or toward the central plane, and two prongs *c'* which are slightly bent away from each other or 75 away from the central plane so that when the wallboard is forced against them, as by pounding, they will enter the wallboard and will be spread laterally, the prongs *c* toward 80 each other and the prongs *c'* away from each other. The prongs *c* may thus have a clenching action as between themselves and also as between each prong *c* and the corresponding prong *c'* on the same side. A 85 single perpendicular prong *d* may be provided for the purpose of preventing slip of the wallboard to one side or the other when it is being applied.

In the use of the improved fastener the 90 prong *d* (which may be left flat if so desired) may first be driven into the studding to hold the fastener in place, and a nail *e* may then be driven into the notch *b*² to 95 securely hold the fastener to the studding. When it has been secured in position the wallboard is placed against the ends of the prongs *c* and *c'* and is forced home, as by 100 blows of a hammer or mallet, against a piece of board laid against the front surface of the wallboard or otherwise by pressure. In this operation prongs *c* are bent inwardly farther toward each other and the prongs *c'* are bent outwardly farther away from each

other, the perpendicular prong *d* being made at the same time to enter the wallboard so as to prevent lateral slip. At the inner end of the nailing slot or notch *b*² the plate is 5 slightly counter-sunk, as shown, to receive the head of the nail.

I claim as my invention:

1. A blind fastener for wallboard, etc., to be placed between the wallboard and studding to which the wallboard is to be fastened, consisting of a thin, flat, metal plate, adapted to be secured to the studding and having struck-up prongs with pointed ends and so bent toward each other that they will 10 enter the wallboard and be bent farther to engage and clench it, and other prongs having pointed ends and so bent away from each other that they will enter the wallboard and be bent farther to engage and retain it,

when the wallboard is forced against the 20 fastener.

2. A blind fastener for wallboard, etc., to be placed between the wallboard and the studding to which the wallboard is to be fastened, consisting of a thin, flat, metal 25 plate, having in one side a notch to receive a fastening means to secure the plate to the studding and on the opposite edge a correspondingly shaped prong bent to engage the studding and provided on the side 30 toward the wallboard with struck-up prongs having pointed ends and so bent that they will enter the wallboard and spread laterally to engage and retain it when the wallboard is forced against the fastener. 35

This specification signed this 23rd day of May, A. D., 1919.

CHARLES A. UPSON.
